UNITED STATES PATENT OFFICE.

WILLIAM H. EHRSTINE AND DAVID E. HESS, OF BRADFORD, OHIO.

COMBINED STEP-LADDER AND IRONING-BOARD.

1,120,800.

Specification of Letters Patent.

Patented Dec. 15, 1914.

Application filed July 2, 1913. Serial No. 777,081.

To all whom it may concern:

Be it known that we, WILLIAM H. EHRSTINE and DAVID E. Hess, citizens of the United States, residing at Bradford, in the county of Miami and State of Ohio, have invented certain new and useful Improvements in Combined Step-Ladders and Ironing-Boards, of which the following is a specification, reference being had to the accompanying drawings.

This invention relates to new and useful improvements in ironing tables and more particularly to a combined ironing table and step ladder, the object of the invention being to provide a combined ironing table and step ladder which can be quickly folded together to occupy minimum space, when not in use or which can be readily set up ready for use and is especially constructed of metal so that the same is comparatively undestructible by fire or the like.

Another object of the present invention resides in the provision of an ironing table of the above character which will possess advantages in points of efficiency and durability, is inexpensive of manufacture and at the same time is simple in construction and operation.

With the above and other objects in view, the invention consists in the novel features of construction, combination and arrangement of parts to be hereinafter more fully described, pointed out in the claims and shown in the accompanying drawings, in which,

Figure 1 is a front elevation of a combined step ladder and ironing board constructed in accordance with our invention, and illustrating the same in its folded position. Fig. 2 is a rear elevation. Fig. 3 is a side elevation of the ironing board. Fig. 4 is a bottom plan view thereof. Fig. 5 is a longitudinal sectional view illustrating the device in its operative position, as an ironing board. Fig. 6 is a detail perspective view of one of the steps of the ladder. Fig. 7 is a detail sectional view through one of the side rails of the ladder. Fig. 8 is an elevation of a portion of the supporting member. Fig. 9 is a side elevation of the device, as set up ready for use as a step ladder; and Fig. 10 is a transverse sectional view of the ironing board.

Referring more particularly to the drawings, 1 indicates the ironing board, one end of which is provided with cut-away por-

tions, to form a tapering end 2. The body of the ironing board 1 is constructed of metal or any other suitable material and the longitudinal edges thereof are provided with a downwardly extending flange 3, the lower edge of which is bent upon itself to provide a second flange 4, so that the lower edge of the flange 3 will present a smooth and unbroken surface. The board 1 is provided upon the under surface thereof with a longitudinal bracing member 5, which is preferably V-shaped in cross section and having outwardly projecting flanges 6 which are riveted or otherwise secured to the central portion of the board 1. The board is further provided with the curved brace members 7, the ends of which are secured to the longitudinal flanges of the board and the intermediate portions thereof integrally formed with the bracing member 5, as shown at 8.

The longitudinal side rails 9 of the step ladder are constructed of metal and are substantially U-shaped, in cross section, the longitudinal edges thereof being bent upon themselves, as shown at 10 to present a smooth and unbroken surface and also to reinforce the side rails. Each of the steps 11 of the ladder are substantially U-shaped in cross section and constructed of metal or any other suitable material, the ends thereof being bent downwardly, at right angles as shown at 12, and riveted or otherwise secured to the longitudinal side rails 9. Each end of the step, when placed in position, would be arranged between the side walls of the longitudinal side rails 9, so that they will be securely held against lateral movement. The steps 11 are suitably braced by means of the triangular brackets 13, one portion of which is riveted or otherwise secured to the longitudinal rails 9 and another portion thereof arranged beneath the steps 11 to securely support the same.

The top step of the ladder 14 comprises a substantially rectangular plate provided with downwardly projecting flanges at each end thereof, as shown at 15, said flanges being pivotally secured to the upper end of the longitudinal side rails 9 by means of the transverse rod 16, said rod having formed integral therewith a supporting member 17. The supporting member 17 comprises the longitudinal side portions 18, the lower ends of which are bent upon themselves, as shown at 19, so that the transverse member 20 will be arranged adjacent the lower ends thereof,

said supporting member being shown in its operative position in Fig. 5 and when it is desired to use the step ladder, the supporting member is swung inwardly toward the ladder and the transverse portion 20 engaged with the catch member 21, carried by the longitudinal portions 9 on the step ladder.

As clearly illustrated in Fig. 5, one end 10 of the ironing board is pivotally secured between the ends of the step 14 and when in its operative position, is supported by means of the opposed rods 22. The lower ends of the rods 22, when in their operative position 15 are mounted for sliding movement upon the longitudinal rods 23, the ends of which are secured to any two of the steps 11. A collar 24 is slidably mounted upon each of the rods 23 and pivotally secured to said collar are the inner ends of the rods 22, said rods being arranged in crossed relation and the outer ends thereof being pivotally secured to the longitudinal flanges 3 and 4 formed upon the board 1. From the above, it will be seen 25 that when the ironing board is swung to a folded position, the inner ends of the rods 22 are moved inwardly upon the rods 23, the pivot point 26 permitting the rods 22 to swing downwardly and be disposed between 30 the board and the ladder.

When the board is swung to its inoperative position as illustrated in Fig. 1, the reduced end portion 2 of the same is arranged 35 between and adapted to be engaged upon opposite sides thereof by the catch members 27 which are secured to the longitudinal side portions of the ladder. From this construction it will be seen that when the device is 40 folded for use as a step ladder, the ironing board is securely held against any movement whatever. It will also be apparent that we have provided a simple and durable combined ironing board and step ladder which, when not used, can be quickly and readily 45 folded to occupy a minimum space.

While we have shown and described the preferred form of our invention, it will be obvious that various changes in the details of construction and in the proportions may 50 be resorted to for successfully carrying our invention into practice, without sacrificing any of the novel features or departing from the scope of the appended claims.

Having thus described this invention, what is claimed is:—

1. A device of the class described including an ironing board and a step ladder, the top step of said ladder having pivotal connection with the upper ends of the side rails of the ladder and the ironing board, downwardly projecting flanges formed at each end of said top step, a U-shaped brace member having its medial portion extending through the upper ends of the side rails of the ladder, and the flanges of the top step, 65 a transverse rod connecting the ends of said brace member, longitudinal guide rods carried by the ladder, supporting rods having one of their ends movably mounted upon said guide rods and their other ends pivotally connected to the ironing board, as and for the purpose set forth.

2. A device of the class described including a step ladder and an ironing board, a top step member having down-turned flanges 75 adapted to be arranged upon opposite sides of the ironing board and ladder, a U-shaped brace member having its intermediate portion extending through the upper ends of the side rails and through the flanges of the 80 top step, whereby to pivotally connect the ladder thereto, a rod extending through the ironing board and flanges to pivotally connect the ironing board thereto, said brace members supporting the step ladder in an 85 inclined position and movable brace members adapted to support the ironing board in a horizontal position.

3. A device of the class described including an ironing board and a step ladder, 90 means for supporting said step ladder in an inclined position, longitudinal guide rods carried by the ladder, supporting braces having their lower ends slidably mounted upon the guide rods and their upper ends 95 pivotally connected to the ironing board, whereby to support said ironing board in a horizontal plane.

In testimony whereof we hereunto affix our signatures in the presence of two witnesses.

WILLIAM H. EHRSTINE.
DAVID E. HESS.
